Application May 4, 1956, Serial No. 41,359

Claims priority, application Germany November 26, 1955

Term of patent 14 years

(Cl. D14—30)

Figure 1 is a top plan view showing the steering wheel embodying my new design.

Figure 2 is a cross sectional view along lines 2—2 of Figure 1.

The characteristic features of my design for the steering wheel disclosed reside in the upper curved spoke portions which extend above the plane of the said steering wheel in the particular relation shown.

I claim:

The ornamental design for a steering wheel, substantially as shown and described.
